[57] CLAIM

The ornamental design for matchbox, as shown and described.

DESCRIPTION

FIG. 1 is a perspective view of a match box showing my new design;

FIG. 2 is a top plan view thereof;

FIG. 3 is a bottom plan view thereof;

FIG. 4 is a front elevation thereof;

FIG. 5 is a rear elevation thereof;

FIG. 6 is a left side elevation thereof;

FIG. 7 is a right side elevation thereof;

FIG. 8 is a perspective view of a first modified form of FIG. 1; and

FIG. 9 is a top perspective view of a second modified form of FIG. 1; the bottom surface being similar to the top.

FIG. 1

FIG. 6

FIG. 2

FIG. 8

FIG. 3

FIG. 9

FIG. 4

FIG. 5
